UNITED STATES PATENT OFFICE.

LEE MILLER, OF CHICAGO, ILLINOIS.

PARACHUTE DEVICE.

1,037,959.

Specification of Letters Patent. Patented Sept. 10, 1912.

Application filed December 7, 1911. Serial No. 664,413.

To all whom it may concern:

Be it known that I, LEE MILLER, a citizen of the United States, residing at Chicago, in the county of Cook and State of Illinois, 5 have invented a new and useful Parachute Device, of which the following is a specification.

The invention relates to aerial life saving devices of the parachute type, and has for 10 its object the provision of a device which can be worn as a part of the clothing of aviators operating aeroplanes, balloons, and the like, or those engaged as steeple jacks at lofty elevations, and subject to danger from fall- 15 ing.

A further object of the invention is to provide, in connection with the parachute, for the automatic and rapid expansion of the same regardless of the position assumed by 20 the wearer in his fall.

Another object of the invention is the combination, in such a device of a size sufficient to support the heaviest man, of the necessary elements to effect its automatic operation in such manner as to entail the least burden because of the weight and the least interference with the movements of the person so equipped.

With these and other objects in view, the 30 invention consists in the construction and novel combination of parts hereinafter fully described, illustrated in the accompanying drawings, and pointed out in the claims hereto appended; it being understood that 35 various changes in the form, proportion, size and minor details of construction, within the scope of the claims, may be resorted to without departing from the spirit or sacrificing materially the advantages of the in- 40 vention.

In the drawings:—Figure 1 represents an elevation of the invention in use. Fig. 2 is a side elevation of the device as carried by the aviator. Fig. 3 is a vertical longitudinal 45 section of the device as worn, taken on the line 3—3 of Fig. 4. Fig. 4 is a vertical transverse section on the line 4—4 of Fig. 3. Fig. 5 is a sectional detail showing the connection between the parachute ring and harness. 50 Fig. 6 is a perspective view of a portion of the harness with the hood removed. Fig. 7 is a similar view showing the ducts and hood but with the yoke removed. Fig. 8 is a development of the outer case. Fig. 9 is a de- 55 tail of the friction clamp. Fig. 10 is a transverse section through the duct in its upper

portion. Fig. 11 is a similar view, taken through the duct in its lower portion. Fig. 12 is a detail section on the line 12—12 of Fig. 2.

Referring to the drawings which are illustrative in character and represent the preferred embodiment of the invention, the reference numeral 1 designates a parachute body, which is the segment of a sphere and has a diameter of about fifteen feet with a depth of from three to five feet. The body is provided at the top with an opening 2 of sufficient size to allow a slight escape of air therethrough to prevent oscillation, and it is 65 also provided with circumferential and radial reinforcing cords 3 and 4. At the outer termini 5 of the radial cords, supporting cords 6 are attached in the usual manner, these supporting cords converging to a connection with the attaching ring 7.

The parachute thus far described is of the usual construction except that it is necessary in order to adapt it for use in this connection to make the same of a special quality of silk, 80 which shall have the least weight consistent with the required strength. I have found it advantageous to use a silk weighing about 2.6 ounces to the square yard and have resistance to rupture of about thirty-two 85 pounds per inch. Material of this sort in a parachute having a diameter of fifteen feet, as stated, weighs about three and one half pounds complete.

The parachute ring 7 is riveted upon its 90 opposite sides, as shown in Figs. 5 and 6 through the flexible strap 8 to the rigid yoke 9, the said strap divided in its lower portion into branches 10 and 11 united at 12 and 13 to a belt 14, adapted 95 to encircle the aviator immediately beneath the arms. Upon the opposite side of the ring the strap is likewise divided into portions 10^a and 11^a secured to the belt at 12^a and 13^a. The yoke 9 extends downwardly 100 in parallel relation to the strap 8 and secured thereto at spaced intervals by the fastenings 15. Each arm of the yoke has loosely mounted on its lower end the shoulder pads 16, which are pivoted to the said yoke by a pivot pin 17, passing through the lower end of the yoke and ears 18 upstanding from the pads. These pads are 105 preferably cup-shaped and lined with a yielding material.

The adjustment of the various parts of the strap and yoke is such that when the strap

14 encircles the body beneath the arms and the pad 16 rests upon the shoulders, the arch of the yoke and the supported ring will be spaced above the head, thus coöperating with the hinged mounting of the pads to enable the wearer to move his head freely, the weight of the device being supported upon the shoulders rather than upon the neck.

10 19 represents the usual tightly fitting hood worn by aviators and arranged to envelop the head with the exception of the face, and is shown as secured beneath the chin by the lacing cords 20. This hood is 15 arranged beneath the strap 8 and the yoke 9 and is provided in its cheek portions with ears 21 and 22 serving a purpose, which will be hereafter described.

20 The hood with its attachments and the belt, strap and yoke constitute a harness by means of which the parachute device is attached to and supported by the body of the wearer. Upon the rear of this harness and preferably upon a downward extension of 25 the hood overlying the wearer's shoulders is supported a frame composed of rigid horizontal side members 23 and horizontal rear members 24, the rear members jointed at 25 and 26 to the respective side members, and the side members pivoted at 27 and 28 to the rear portion of the hood. Elastic cords 29 connect the upper and lower members of the frame at the junction points of the rear and side members, 30 while elastic cords 30 extend from the junction points of the lower frame members to the rear portion of the belt and elastic cords 31 extend from the junction points of the upper frame members to the hood, connecting therewith at a point 32 adjacent the ears of the wearer.

45 An inflater 33 of flexible material is arranged at the rear of the hood and extends from a point above the crown of the hood to the space embraced within the frames. This inflater in its upper portion has a single channel 34 with its walls composed of flexible material, the side walls 35 folded longitudinally, bellows-like, in order to render the same extensible laterally when inflated. In the lower portion this inflater is divided longitudinally by a membrane 36, which separates the interior of the duct into two channels 37 and 38, the side walls of 50 which are longitudinally folded at 39 and 40. At the lower end portion within the frame the membrane is extended to a connection with the lower rear frame member, and the edge walls 40 of the channel nearest 55 the head are secured to the lower side members of the frame, thus making of the said frame a rigid distending device holding the mouth of the inflater open and flared downwardly. The rear wall 41 of the inflater at 60 its lower end is connected at 42 to the upper

side members of the frame and thence extending across the frame, while the membrane at a point above its lower edge carries an extension 36^a curved upwardly and connected to the rear upper member of the 70 frame, thus forming a distended upwardly turned flaring mouth for the rear channel of the inflater.

It will be observed that upward currents of air will enter the forward channel of the 75 inflater in its lower portion and thence traverse the upper channel of the same, the action of the air thereon tending to press the membrane to the rear and prevent return currents through the rear channel, whereas 80 downward currents of air will enter the upwardly flaring mouth of the rear channel, passing to the single channel of the upper portion and tending to press the membrane forward so as to close the front channel. 85 This provision is intended to meet the conditions present during a fall, directing the relative upward rush of air into and through the inflater whether the wearer falls head first or feet first.

90 The parachute body is arranged to be folded bellows-fashion along the arcs of the great circles passing through the apex, as shown in Fig. 4. It is then folded endwise together with the cords 6 alongside the upper extension of the inflater 33 without folding the latter, and as thus folded is laid upon the yoke 9 above the head.

95 A case 43 is provided, which is composed of a body portion of substantially the shape 100 shown in Fig. 8, having one side incut and provided with gores 44 stitched together to form the bands 45 to fit the forehead, the body being provided at its four corners with friction clamps 46 and 46^a, each of which consists of two members 47 and 48 pivoted at 49 and arranged to grip with their jaws 50 the ears 21 heretofore referred to as carried by the hood 19, said jaws pressed together by the spring 51. The case thus 110 formed is placed above the folded parachute, the band drawn across the forehead and the two front clamps 46 engaged with the ears 22, the rear portion of the case is then drawn forward to envelop the rear portion of the 115 folded parachute and inclosed inflater and the clamps 46^a attached to the ears 21, thus protecting the folded parachute from disarrangement by air currents met with from in front during travel through the air in a 120 normal manner.

125 The equipment of the aviator when ready for flight is represented in Fig. 2, from which will be seen that no interference is presented to the free movements of the 125 wearer and the appearance is not such as to excite particular attention from observers. If the aviator thus equipped falls from the balloon or aeroplane, or from other high elevations feet foremost the resultant up- 130

wardly rushing air currents will enter the forward duct of the inflater expanding its bellows-like sides to their full capacity and discharging, as will be seen from Fig. 3, into the folds of the parachute above his head. If he falls head first, the upwardly rushing air will enter the rear duct acting in like manner to extend the walls to the full capacity of the said duct and discharging at the same point into the folded parachute. The expansion of the duct walls exerts an outward pressure upon the case more than sufficient to release the clamps 46^a from the ears 21 and the expansion of the folded parachute will release the clamps 46 from the ears 22, thus throwing off the enveloping case and freeing the parachute, which being rapidly expanded by the inrushing air assumes the position shown in Fig. 1 and supports the weight of the man. The capacity of the inflater is such that the parachute will be fully extended within the first few yards of descent, so that if the elevation is sufficient to cause material injury, the parachute will expand and break the fall. If the distance is not sufficient to allow the parachute to expand, the arrangement of the same upon the head of the wearer will serve as a cushioning device to prevent injury from contact with the ground or from parts of the machine striking the head of the person.

It will be understood that if the man when he starts to fall is in full possession of his faculties, he need not wait for the automatic release of the hood but may snatch it off with his hand. If, however, he is panic stricken or is affected with mountain sickness causing unconsciousness, the duct 40 will work automatically and with certainty. With the inflater capacity illustrated and found advantageous by test the lateral pressure upon the walls of the inflater caused by the inrushing air currents and acting to release the outer case rapidly increases with the descent from a pressure of slightly more than a half pound to the square foot at the end of a fall of five feet; three pounds at the end of twenty feet; ten pounds at the end of seventy-five feet, and fourteen pounds at the end of one hundred feet, from which it will be seen that the disengagement of the friction clamps from the ears 21 and 22 and the consequent release of the hood and expansion of the parachute is certain to follow a fall whatever be the initial position of the aviator.

The provision of the elastic connection of the frame-work with points above and below the same and at each side thereof, guards against the breaking of said frame-work by striking against obstructions while being worn, the elastic cords yielding to an extent sufficient to prevent breaking of the frame which might otherwise result.

What is claimed is:—

1. In a device of the class described, the combination with a foldable parachute having suspension cords, and a harness arranged to be attached to the body of the aviator and to the suspension cords, of an inflater comprising an air duct having expandible walls and discharging within the folds of the parachute, a case enveloping the collapsed inflater, and detachable means securing the case in position. 75

2. In a device of the class described, the combination with a foldable parachute having an attaching ring for suspension cords, of a harness arranged to be attached to the aviator's body and to the ring and supporting the folded parachute above the head, and an inflater carried by the harness and comprising an upwardly tapering duct having expandible walls and terminating within the folds of the parachute, a case enveloping the parachute and inflater, and releasable means connecting the case to the harness. 85

3. In a device of the class described, the combination with a foldable parachute having suspension cords, and a harness arranged for attachment to the body of the wearer, said harness comprising a belt passing beneath the arms, flexible members extending from the belt on each side and above the head to a connection with the suspension cords, and rigid members supported upon the shoulders and extending above the head beneath the folded parachute, of an inflater comprising an air duct having expandible walls and discharging within the folds of the parachute, a case enveloping the collapsed inflater, and detachable means securing the case in position. 95

4. In a device of the class described, the combination with a foldable parachute having a central upper vent, suspension cords, and an attaching ring, a harness arranged to be attached to the body of the aviator and comprising a belt, straps connected to said belt and extending from each side thereof above the head to a connection with the ring, pads to overlie the shoulders, a rigid yoke bearing upon the pads and extending above the head beneath the ring as a support for the folded parachute, a hood enveloping the head and extending downwardly over the shoulders, of an inflater mounted in substantial vertical position upon the rear depending portion of the hood and extending from the lower portion thereof to a point above the crown and within the folds of the parachute, said inflater having extensible normally collapsed walls, a case enveloping the parachute and inflater, and a releasable connection between the case and the hood. 110

5. In a device of the class described, the combination with a foldable parachute hav- 125

ing a central upper vent, suspension cords, and an attaching ring, a harness arranged to be attached to the body of the aviator and comprising a belt, straps connected to said belt and extending from each side thereof above the head to a connection with the ring, pads to overlie the shoulders, a rigid yoke bearing upon the pads and extending above the head beneath the ring as a support for the folded parachute, a hood enveloping the head and extending downwardly over the shoulders, of an inflater mounted upon the rear of the harness and comprising an air duct extending in a substantially vertical direction and discharging within the folds of the parachute, said duct having normally collapsed extensible walls terminating below in an outwardly flaring mouth distended by the frame, a case enveloping the folded para-
